UNITED STATES PATENT OFFICE.

GEORGE C. JENSEN, OF OAKLAND, CALIFORNIA.

SHIFTER-DEVICE CONTROL-LOCK AND LOCK-OPERATING MEANS.

1,317,191.

Specification of Letters Patent. Patented Sept. 30, 1919.

Application filed June 25, 1919. Serial No. 306,700.

To all whom it may concern:

Be it known that I, GEORGE C. JENSEN, a citizen of the United States, residing at Oakland, in the county of Alameda and State of California, have invented certain new and useful Improvements in Shifter-Device Control-Lock and Lock-Operating Means, of which the following is a specification.

10 The present invention relates to that type of shifter device lock constructions illustrated in my pending application Serial No. 268,191 filed Dec. 24, 1918, and to the devices illustrated in Letters Patent Nos. 1,296,397, and 1,296,398 granted to me March 4, 1919. The particular improvement in the present construction being in the provision of a shifter device lock which is in operative position during such time 20 as the vehicle clutch is engaged, is released on the disengagement of the clutch, and in connection with which is operatively disposed a member serving as an interlock and retainer for the shifting devices during the 25 operative movement thereof. To provide a locking construction wherein the same is capable of being locked or precluded from operative movement only at such times as the shifter devices are moved to a predetermined position.

With the above mentioned and other objects in view the invention consists in the novel construction and combination of parts hereinafter described illustrated in the accompanying drawings, and set forth in the claims hereto appended, it being understood 35 that various changes in the form, proportion, size and minor details of construction within the scope of the claims may be 40 resorted to without departing from the spirit or sacrificing any of the advantages of the invention.

In the drawings,

Figure 1 illustrates a view in side elevation of one embodiment of my invention disclosing the clutch-operating pedal and the connection between the same and the locking bolt.

Fig. 2 is a vertical sectional view taken centrally through the shifter device lock illustrated in Fig. 1.

Fig. 3 is a sectional view taken on line 3-3 of Fig. 2.

Fig. 4 is a transverse sectional view taken 55 through the lower end of the locking bolt and shifter devices illustrating the locking

bolt in its full depressed position and disclosing the interlocking member operated thereby.

Fig. 5 is a view similar to Fig. 4, with one 60 of the shifter devices moved from its position as illustrated in Fig. 4 and wherein the locking bolt is precluded from downward movement to the end of its stroke.

Fig. 6 is a diagrammatic view with the 65 shifter devices and bolt in position illustrated in Fig. 5.

Referring more particularly to the several views of the drawings wherein like characters of reference designate corresponding parts, the numeral 1 indicates a suitable casing of any well-known type, within which is positioned any suitable form of releasing clutch member, the same being operated by the actuation of a pedal or lever 2 either of the band or foot operated type, the present universal form being of the foot operated type. The lower end of the pedal is illustrated as co-operating with a shaft 3 carrying a crank 4, to which is 75 pivotally connected a tubular sleeve or member 5.

To the rear of the case 1 is secured in any suitable manner, a gear case for housing 6, of any suitable type, for containing the variable speed power transmitting gears or mechanism of the motor driven vehicle, and the upper open top of the case is preferably closed by a cover 7, with which is associated the gear shifter devices 8, preferably 80 in the form of rods arranged in parallel spaced relation. While the case 6 is illustrated as being connected directly to the member 1, and the cover 7 thereof carrying the shifter devices 8, it is to be understood 95 that the gear case 6 may be a unit of itself, and if desirable the shifter devices 8 may be incorporated directly therein instead of the cover therefor.

The shifter devices 8 are illustrated as 100 being provided in adjacent faces with a plurality of stops, the stops being illustrated in the form of depressions 9 and 10, the depressions 9 being of a greater depth than the depressions 10, for the hereinafter 105 described purpose.

The shifter devices 8 are supported at opposite ends in suitable bores or channels and the cover 7 is formed in its body with a transverse channel 11, a portion of which 110 connects said shifter devices 8 providing a walled opening between the same. The

outer end of the channel 11 is closed in any suitable manner as by a plug 12.

Freely movable within the channel 11 and positioned between the shifter devices 8 is a suitable disengageable member 13 formed preferably in two sections, one of said sections being provided with a bore 14, within which is received the tubular extensions 15 of the other section, said bore and extension providing a sliding connection between the sections, which permits of the extension and contraction of the disengageable member. A coiled spring 16 is received within the tubular extension 15 with its opposite ends abutting against the respective members of the member 13, said spring tending to force said members apart, and said members are provided with limiting shoulders 17, which limit the contraction of the sections forming the members 13. Thus it will be apparent that a member is positioned between the shifter devices 8, which is capable of expansion to be received at its opposite ends in the depressions 9 or 10 and is adapted to be compressed to a given length, the compression length of said member being approximately the distance between the shifter devices 8 plus the depth of one stop, as illustrated in Figs. 4, 5 and 6 of the drawing.

The shifter devices are selectively operated by the actuation of a well-known control mechanism or lever 18, Fig. 1 of the drawings, and on the operation of one of said devices to move one of the depressions from coöperation with one end of said disengageable member 13 and to position another stop into coöperation therewith. The action is as follows: Immediately prior to the shifting of one of the devices 8 the opposite ends of the member 13 are forced by the spring 16 into engagement with the respective stops lying at the opposite ends of the bore 11, thus retaining the shifter devices in their adjusted position prior to the manual operation of one of said devices. On the movement of the desired shifter device the members forming said disengageable member 13 are, due to the movement of the desired shifter device to expel one end of the member 13 from the stop within which it is received telescoped until the shoulders 17 abut, which operation forces one end of the member 13 into its associated stop while the other member is riding on the surface of the moved or operated shifter device 8 lying between adjacent stops thereon, thus an interlock is provided between the shifter devices during the operation of one or the other thereof.

The bore 11 at a point between the shifter devices 8 and preferably at a point to intersect the path of movement of one of said shifter devices, is intersected by another

bore 19 formed in the wall surface of the cover 7 and preferably disposed in a vertical plane, said bore being open at its upper end. Mounted for reciprocation within the bore 19 adjacent its lower end, is a locking bolt 20, the lower end of which is provided with a locking tongue 21 disposed intermediate opposite faces of said bolt 20, said tongue adapted on the depression of the bolt for reception within one of the stops 10 of its associated shifter device 8, said bolt when in the latter position being precluded from further depressed movement by the engagement of the shoulder 22 at the upper end of said tongue 21 with the upper surface of the solid portion of the shifter device 8 adjacent the stop 10. This limiting being illustrated in Fig. 5. On the positioning of one of the stops 9 beneath said bolt 20, the same is capable of being depressed a greater distance than when the stop 10 coöperates therewith, as the wall of the stop 9 corresponds with and is in alinement with the peripheral surface of the bolt 20, this further depressed movement being illustrated in Fig. 4. On the depression of the bolt 20, the tongue, as explained, is received in the stop which has been moved into alinement with the bolt, and said tongue in this position engages one end of the freely movable member 13 and forces the opposite end thereof into engagement with the stop adjacent said opposite end, thus the member precluding movement of one shifter device.

This forcing of the freely movable member 13 into coöoperative engagement at its end with a stop in register therewith takes place on the depression of the bolt 20 its full length as illustrated in Fig. 4, or, for a portion of its stroke, as illustrated in Fig. 5.

As illustrated in the present embodiment of the invention the bolt is raised during each depression or operation of the clutch pedal 2 to release the clutch permitting the shifter devices to be selectively operated during such time as the clutch is disengaged, and in accomplishing this result, I prefer to employ the following mechanism: The bolt 21 is provided on its surface above the tongue 22 with a rack 23 with which engages a pinion 24 disposed preferably at an angle to the bolt and rotatably mounted in a recess 25 formed in the surface of the cover 7. The pinion is retained in position preferably by a set screw 26, the inner end of which projects into an annular groove 27 adjacent one end of the pinion 24, and said pinion carries at its outer end a crank 28 pivotally connected through a link 29 with the crank 4 associated with the lever or pedal 2. This latter connection being made by passing the end of the link 29 through the sleeve 5, and positioning on each side of said sleeve 5

compression springs 30 held under tension by the adjustment of nuts or other means 31. Thus it will be apparent that when the locking bolt is precluded from operative movement as hereinafter described, the clutch, due to the positioning of the springs 30 between the ends of the sleeve 5 thereof and the nuts 31, is capable of operation independently of the operation of the bolt, and means are provided permitting the clutch elements to be adjusted to insure proper engagement and disengagement thereof dependent upon the throw of the lever 2 without requiring the adjustment of the nuts 31 to insure the proper operation of the locking bolt.

As illustrated, the locking bolt is of a length considerably less than that of the bore 19, and in the upper portion of said bore is mounted for manual movement independently of the movement of the bolt 20 a longitudinally movable bolt locking plunger 32, the upper end of which, when the bolt is in operative or released position is adapted to project beyond the upper end of the bore 19, as illustrated in Figs. 1 and 2 of the drawings. The bolt locking plunger 32 is preferably formed centrally of its lower end with the cup or recess 33, in which is received one end of a coil spring 34, the lower end of which surrounds a pin 35 projecting centrally from the upper end of the bolt 20 and receivable in said bore 33, said spring normally maintaining the bolt locking plunger 32 in its raised or inoperative position and the bolt 20 depressed. The bolt locking plunger 32 is guided in its movement and precluded from rotation by a suitable set or guide screw 36, projecting into the bore 19 and into a vertical groove 37 in the body of the plunger 32.

Means are provided for locking the bolt locking plunger 32 in its depressed position at such time as the bolt 20 is in its full depressed position as illustrated in Fig. 4, this full depressed position being preferably when the transmission mechanism operated by the shifter devices, is in what is commonly termed neutral or non-power transmitting position, and in accomplishing this result, I prefer to employ the following mechanism: Mounted in a bore 38 is a plunger locking pin 39, one end of which is normally forced outwardly into contact with the surface of the bolt locking plunger 32 by the action of a coil spring 40, and said pin on the full depression of the bolt locking plunger 32 is received at its outer end in a recess 41 in the surface of the bolt locking plunger 32, but should the bolt locking plunger 32 be depressed during such time as the bolt 20 is in engagement with one of the stops 10 as illustrated in Fig. 5, the movement of the locking plunger will not be sufficient to permit the lower edge of the recess

41 to clear the lower edge of the tongue 42 of the plunger 39, thus it is impossible in the construction as illustrated to lock the shifter devices when the same are moved to place the transmission gears controlled thereby into power transmitting position. In releasing the locking pin 39 I prefer to employ a key operated barrel 43 of any well known type, the lower end thereof carrying an eccentrically disposed pin 44 operating in a depression 45 in the upper surface of the pin 39, thus on the rotation of the barrel 43 the pin 39 will be retracted in its bore 38, and the tongue 42 thereof will be disengaged from its recess 41 permitting the spring 34 to restore the bolt locking plunger to its normal or inoperative position.

In my present construction, it will be apparent, that I have provided a means which is operated on each operation of the clutch member when the same is moved to released or disengaged position to permit the selective control of the shifter devices, and during such selective operation of the shifter devices the device not operated is precluded from movement by an interlock and during the interval of time between the operation of the clutch and the selective movement of said shifter devices, said shifter devices are retained from accidental movement. I have also provided a means whereby the locking bolt is capable of being locked from released movement only at such time as the shifter devices are in a predetermined position, this position in the present embodiment of the invention being what is commonly termed neutral.

Having thus described my invention what I claim is:

1. In combination with a plurality of longitudinally movable shifter devices, each provided with a stop, a movable bolt adapted when in locking position to engage with the stop of one of the shifter devices, a disengageable member actuated by said bolt when moved into locking position for engaging the stop of the opposing shifter device, whereby said devices are held locked against longitudinal movement, said disengageable member being formed of a plurality of parts adapted on the movement of said bolt to unlocked position for coöperation with the respective devices to retain said devices in their adjusted position.

2. In combination with a pair of spaced independently movable shifter devices, each provided with a stop, a locking bolt capable of movement to engage one of said shifter devices to lock the same from operative movement, and an interlocking and retaining means interposed between said shifter devices and capable, on the movement of the bolt to unlocked position, of coöperation with the stop of one shifter device on the movement of the other shifter device.

- to move its stop from coöperation with the end of said member, and of expansion to retain said shifter devices in their adjusted position on the registering of the stops 5 thereof with the opposite ends of said means, said bolt adapted on its movement into coöoperative relation with its associated stop to force said means into locked engagement with the other shifter device.
3. In combination with a member provided with a pair of spaced shifter devices independently movable in a parallel plane into a plurality of positions, means lying between said devices and yieldably separating 10 said devices in their adjusted position, and means capable of operation to coöperate with one of said stops to prevent movement of its associated device and to compress said retaining means to force the same into locked contact with the other of said devices to prevent movement thereof.
4. In combination with a pair of independently movable shifter devices, each provided with a stop, an extensible member 15 freely movable between said shifter devices and the ends thereof adapted for coöperation with said stops, the minimum length of said member being approximately equal to the distance between said devices and the depth of one stop, a bolt adapted for movement into coöperation with the stop of one of said shifter devices for locking the same from movement and for filling said stop, 20 whereby the opposite end of said member is forced thereby into coöperation with the stop of the other shifter device to lock said shifter device from movement, said expandable member adapted on the withdrawal 25 of said bolt from its associated stop to expand and lie with its opposite ends in contact with the stops of the opposing shifter devices.
5. In combination with a longitudinally movable shifter device provided with a plurality of stops, a movable locking bolt capable of selective coöperation with said stops on the movement of the shifter device to place the same in coöperation with said bolt, 30 means for moving said bolt into and out of operative position and means coöperating with said bolt and capable of operation to lock the same from movement when in engagement with one of the stops, the means being precluded from movement to lock said bolt on the last coöperation with the remainder of said stops.
6. In combination with a shifter device provided with a stop, a locking bolt capable 35 of movement for engaging said stop to lock said shifter device from movement, means for operating said bolt into and out of operative position with said shifter devices, and a bolt locking plunger independent of said locking bolt and capable of operation 40 to lock said bolt in engagement with said stop and preclude movement thereof to inoperative position on the actuation of said bolt operating means.
7. In combination with a shifter device 45 provided with a stop, a locking bolt capable of movement for engaging said stop to lock said shifter device from movement, means for moving said bolt into engagement with said stop, a bolt locking plunger independent of said locking bolt and capable of movement to lock the bolt in engagement with said stop, and releasable lock controlled means for locking said plunger in its latter 50 position.
8. In combination with a shifter device provided with a plurality of stops, a movable locking bolt for selective coöperation therewith to preclude movement of said shifter device, the movement of said bolt into coöoperative engagement with one of said stops being greater than its movement into coöoperative engagement with the other of said stops, and means for locking said bolt when in coöoperative engagement with the stop permitting the greater movement thereof into locking position.
9. In combination with a shifter device provided with a plurality of stops, a movable locking bolt for selective coöperation therewith to preclude movement of said shifter device, the movement of said bolt into coöoperative engagement with one of said stops being greater than its movement into coöoperative engagement with the other of said stops, and releasable means for locking said bolt in coöoperative engagement with one of said stops, the movement of said means into its locking position being dependent on the degree of movement of said bolt.
10. In combination with a shifter device, provided with a plurality of stops, a movable locking bolt for selective coöperation therewith to preclude movement of said shifter device, foot operated means for actuating said bolt, the movement of said bolt into coöoperative engagement with one of said stops being greater than its movement into coöoperative engagement with the other of said stops, and a bolt locking plunger capable of operation, dependent on the degree of movement of said locking bolt to lock said bolt in engagement with but one of said stops.
11. In combination with a shifter device provided with a stop, a movable locking bolt for coöperation with said stop to retain the shifter device in its adjusted position, manually operated means for releasing said bolt, a bolt locking plunger independent of said locking bolt and capable of movement to preclude the releasing movement of said locking bolt, releasable means for retaining

- 5 said bolt locking plunger in locked position, and a spring interposed between said bolt and bolt locking plunger for normally retaining said plunger in released position and 5 said bolt in locking position.
- 10 12. In combination with a shifter device provided with a stop, a longitudinally movable locking bolt for coöperation with said stop to retain the shifter device in its adjusted position, manually operated means for releasing said bolt, a longitudinally movable bolt locking plunger arranged in alignment with said bolt and independent thereof, said plunger capable of movement to 15 coöperate with said locking bolt to preclude the releasing movement thereof, a spring interposed between said bolt and bolt locking plunger for normally maintaining said plunger in released position and said bolt in locking position, and releasable means for locking said plunger in locking position.
- 20 13. In combination with a shifter device provided with a stop, a movable locking bolt for coöperation with said stop to retain the shifter device in its adjusted position, a movable bolt locking plunger independent of said locking bolt and capable of movement when said bolt is in engagement with said shifter device to engage said locking 25 bolt and preclude releasing movement thereof, releasable lock controlled means for locking said plunger in position to lock said bolt from movement, and means interposed between said locking bolt and plunger for normally maintaining the same separated.
- 30 14. In a power transmitting mechanism including a clutch operating mechanism, and a gear shifting device provided with stops, a locking bolt capable of coöperation with said 35 stops to preclude operation of said shifter device, a connection between said clutch operating means and bolt whereby the bolt is moved out of engagement with said stops on the movement of said clutch operating 40 mechanism to release the clutch, a locking plunger capable of movement to preclude 45
- movement of said bolt out of engagement with said stops on the movement of said clutch operating mechanism to release the clutch, and releasable lock controlled means 50 for retaining the plunger in its latter position.
- 55 15. In a power transmitting mechanism including a clutch operating mechanism, a pair of parallel spaced independently movable shifter devices each provided with a stop, a locking bolt capable of movement for engaging one of said shifter devices to lock the same from operative movement, a freely movable device interposed between said shifter devices and moved by said bolt when in this latter position into coöperation with the stop in the other shifter device to lock the same from movement, and a connection between said clutch operating mechanism 60 and said bolt for moving said bolt from engagement with its shifter device on the release of the clutch.
- 65 16. In a power transmitting mechanism including a clutch operating mechanism, a pair of parallel spaced independently movable shifter devices each provided with a stop, a locking bolt capable of movement for engaging one of said shifter devices to lock the same from operative movement, a freely movable device interposed between said shifter devices and moved by said bolt when in this latter position into coöperation with the stop in the other shifter device to lock the same from movement, a bolt locking plunger 70 adapted for manual operation to preclude said movement of said locking bolt on the release of said clutch, and releasable lock controlled means for locking said plunger on this latter position.
- 75 In testimony whereof I have signed my name to this specification in the presence of two subscribing witnesses.
